UNITED STATES PATENT OFFICE.

HOWARD STOKES, OF TRENTON, NEW JERSEY, ASSIGNOR TO ADVERTISERS PRODUCTS CORPORATION, A CORPORATION OF NEW JERSEY.

CHANGE TRAY.

Application filed December 30, 1924. Serial No. 758,964.

To all whom it may concern:

Be it known that I, HOWARD STOKES, a citizen of the United States, residing at Trenton, in the county of Mercer and State 5 of New Jersey, have invented certain new and useful Improvements in Change Trays, of which the following is a specification.

The present invention appertains to a change tray and has for its principal object 10 to incorporate means therein for illuminating the tray when change is taken therefrom for showing advertising matter.

The invention further aims to provide a 15 very simple and efficient construction of this nature which is reliable in operation, inexpensive to manufacture, attractive in appearance, strong, durable, and well adapted to the purpose for which it is designed.

With the above and numerous other objects in view as will appear as the description proceeds, the invention resides in certain novel features of construction, and in the combination and arrangement of parts 20 as will be hereinafter more fully described and claimed.

In the drawing:

Figure 1 is a top plan view of the invention,

Figure 2 is a longitudinal vertical section 30 taken therethrough substantially on the line 2-2 of Figure 1,

Figure 3 is a top plan view of the base, and Figure 4 is a bottom plan view of the top.

Referring to the drawing in detail it will 35 be seen that the change tray includes a base B and a top T. The base B is preferably mounted on feet 5 and is provided in its upper surface with a compartment 6 and another compartment 7 communicating therewith but not as deep as 6. The compartment 6 is adapted to receive a battery 8 having a spring terminal 9 extended into the bottom of compartment 7 and another spring terminal 10 at its top. A leaf spring 40 11 is attached to the top of the base by means of a screw 12 and inclines upwardly therefrom extending across the battery in engagement with the spring terminal 10. This spring terminates adjacent the forward end of the base. A lamp socket 14 is positioned within the compartment 7 above the spring contact 9 being held in place by a bracket arm 15 which is fastened to the upper surface of the base by a screw 16. 45 An incandescent electric bulb or lamp 17 is positioned within the socket 14 so as to rest on the spring contact 9. A screw or fixed contact 18 is mounted on the upper surface of the base adjacent the forward end thereof immediately below the terminal of the 60 spring 11. A wire 19 is connected at one end to the screw contact 18 and at its other end to the screw 16 so that when the spring 11 is depressed a circuit will be formed including the battery 8, the spring terminal 10, the spring 11, the fixed contact 18, wire 19, the screw 16, bracket arm 15, socket 14, electric bulb 17, and spring contact 9.

The top T is preferably formed of aluminum so that it may be extremely light but 70 of course other suitable material may be used. This top is of a hollow construction and is provided at its rear end with a pair of notched lugs 21 adapted to engage screws 22 on the upper surface of the base adjacent the rear end thereof whereby the forward end of the top may be moved toward or away from the base. The upper portion of the tray is slanted so as to provide a change receiving pocket 24 with sloping 75 walls so that change may be easily placed therein and easily removed therefrom. This pocket is located adjacent the forward end of the device. A rubber buffer 25 is provided on the inside of the top T and engages the terminal of the spring 11. This spring has sufficient tension to support this top so that the spring is out of engagement with the fixed contact 18. As soon as the fingers, 80 however, are placed on the top or tray for the purpose of taking change therefrom the spring is depressed so as to engage the fixed contact 18 and close the circuit for causing the illumination of the bulb 17.

An opening 28 is provided in the upper wall of the tray proper or top T and at the forward edge of this opening there is provided a flange 29. A pair of transparent panels 30 with a strip 31 therebetween are rested at one edge on the flange 29 while a screw on the inside of the top is engaged therewith as at 32 and supports a washer 33 which engages the bottom panel thus holding these panels over the opening 28 and thus when the bulb 17 is lighted the strip is 90 illuminated so that words printed thereon may be read.

A threaded opening 35 is provided on the under surface of the forward edge of the top T for the reception of a bolt 36 which 100

extends through an opening 37 provided in the base which opening is enlarged as at 38 at its bottom so as to provide a shoulder 39 against which the head of the bolt rests. 5 By turning this bolt it will be seen that the tray at its free end may be moved closer to the base on the spring will be allowed to move it farther therefrom. Thus the distance between the free end of the spring 11 10 and the fixed contact 18 may be regulated. It is desirable that this space be very small that the slightest contact with the top of the tray will be sufficient to throw the circuit and cause the illumination of the sign 15 between the panels 30.

It will be apparent that I have devised a new and useful change tray which has a simple and efficient construction so as to be illuminated when change is taken therefrom for the purpose of making visible a 20 sign or the like which may be utilized for advertising.

The preferred embodiment of the invention has been disclosed in detail and it is 25 desired to point out that numerous changes in the details of construction, and in the combination and arrangement of parts may be resorted to without departing from the spirit or scope of the invention as herein- 30 after claimed or sacrificing any of its advantages.

Having thus described my invention, what I claim as new is:

1. A change tray of the class described 35 including in combination a base, a hollow top in the form of a tray top proper pivoted at one end to the base, a spring on the base engaging the top to hold its free end normally a slight distance from the adjacent 40 end of the base, a fixed contact on the base below the end of the spring to be engaged thereby when the free end of the top is moved downwardly in taking change therefrom, a source of illumination on the base, 45 and a circuit including said source of illumination and the spring and contact, said base provided with an opening enlarged at the bottom thereof, a bolt passing through the opening so that its head engages the shoulders 50 formed at the juncture of the enlargement of the opening which rests thereon, a threaded opening in the bottom of the top for receiving the bolt whereby the bolt may be adjusted for varying the distance between the free end of the top and the adjacent end of the base, and a panel fitted in 55 the last mentioned opening, said base provided with a compartment on its upper surface for receiving a battery forming part of said circuit.

2. A change tray of the class described 60 including a base, a hollow top in the form of a tray top proper pivoted at one end to the base, a spring on the base engaging the top to hold its free end normally a slight distance from the adjacent end of the base, a fixed contact on the base below the end of the spring to be engaged thereby when the free end of the top is moved downward- 65

ly in taking change therefrom, a source of illumination on the base, and a circuit including said source of illumination and the spring and contact, said base provided with an opening enlarged at the bottom thereof, 70 a bolt passing through the opening so that its head engages the shoulders formed at the juncture of the enlargement of the opening which rests thereon, a threaded opening in the bottom of the top for receiving the bolt whereby the bolt may be adjusted for varying the distance between the free end of the top and the adjacent end of the base, 75 said top provided with an opening, and a panel fitted in the opening.

3. A change tray of the class described including in combination a base, a hollow top in the form of a tray top proper pivoted at one end to the base, a spring on the base engaging the top to hold its free end normally a slight distance from the adjacent end of the base, a fixed contact on the base below the end of the spring to be engaged thereby when the free end of the top is moved downwardly in taking change 80 therefrom, a source of illumination on the base, and a circuit including said source of illumination on the base, and a circuit including said source of illumination and the spring and contact, said base provided with an opening enlarged at the bottom thereof, 85 a bolt passing through the opening so that its head engages the shoulders formed at the juncture of the enlargement of the opening which rests thereon, a threaded opening in the bottom of the top for receiving the bolt whereby the bolt may be adjusted for varying the distance between the free end of the top and the adjacent end of the base, and a panel fitted in 90 the last mentioned opening, said base provided with a compartment on its upper surface for receiving a battery forming part of said circuit.

4. A change tray of the class described 95 including in combination a base, a pair of screws rising from the base at one end thereof, a top in the form of a tray proper having notched lugs extending from one end to engage the screws so that said top will be pivotally mounted on the base, the top having a transparent panel carrying advertising matter, a circuit closer on the base normally holding the free end of the top a slight distance from the adjacent end of the base, a source of illumination on the base for said panel, and a circuit including 105 said source of illumination and the circuit closer.

5. A change tray of the class described 110 including in combination a base, a pair of screws rising from the base at one end thereof, a top in the form of a tray proper having notched lugs extending from one end to engage the screws so that said top will 115

be pivotally mounted on the base, a circuit closer on the base embodying a normally raised spring contact engaging and normally holding the free end of the top a slight distance from the adjacent end of the base, a source of illumination on the base, a circuit including said source of illumination and the circuit closer, means for adjusting the distance at which the circuit closer will hold the free end of the top from the base 10 and a transparent panel in the top.

In testimony whereof I affix my signature.

HOWARD STOKES.
